(57) CLAIM

The ornamental design for a light therapy device, as shown and described.

DESCRIPTION

FIG. 1 is a top perspective view of a first embodiment of the light therapy device;

FIG. 2 is a bottom perspective view of the light therapy device of FIG. 1;

FIG. 3 is a top plan view of the light therapy device of FIG. 1;

FIG. 4 is a bottom plan view of the light therapy device of FIG. 1;

FIG. 5 is a first side view of the light therapy device of FIG. 1;

FIG. 6 is a second side view of the light therapy device of FIG. 1;

FIG. 7 is a first end view of the light therapy device of FIG. 1;

FIG. 8 is a second end view of the light therapy device of FIG. 1;

FIG. 9 is a top perspective view of a second embodiment of the light therapy device;

FIG. 10 is a bottom perspective view of the light therapy device of FIG. 9;

FIG. 11 is a top plan view of the light therapy device of FIG. 9;

FIG. 12 is a bottom plan view of the light therapy device of FIG. 9;

FIG. 13 is a first side view of the light therapy device of FIG. 9;

FIG. 14 is a second side view of the light therapy device of FIG. 9;

FIG. 15 is a first end view of the light therapy device of FIG. 9; and,

FIG. 16 is a second end view of the light therapy device of FIG. 9.

The broken lines in the drawings depict portions of the light therapy device and form no part of the claimed design.

1 Claim, 12 Drawing Sheets
